UNITED STATES PATENT OFFICE.

DAVID WOLFE BRUCE, OF NEW YORK, N. Y.

DESIGN FOR TYPE.

SPECIFICATION forming part of Design No. 15,034, dated June 3, 1884.

Application filed April 10, 1884. Term of patent 14 years.

To all whom it may concern:

Be it known that I, DAVID WOLFE BRUCE, of the city, county, and State of New York, have invented and produced a new and original Design for a Font of Printing-Type, of which the following is a specification.

The nature of my design is clearly shown in the accompanying typographic impression, to which reference is made; and it consists of a letter showing a series of heavy and light lines.

In the A, M, and X the left-hand up-and-down portion is light, the right-hand up-and-down portion is heavy, the cross-line light. In the U, V, W, and Y the left-hand up-and-down portions of the letter are heavy, the right-hand portions light. In the C, G, O, and Q the letters are composed of the heavy and light inclined lines, which, in the case of O and Q, are placed transversely. In the B and D the lower portion of the letter upon the

right is light, the upper portion heavy. In the J the lower portion upon the left is light, the upper portion heavy. Both the up-and-down portions of the V are light, the cross-line heavy. The connecting-line of the H is light, the up-and-down portions heavy. In the K the upper right-hand portion of the letter is light, the lower portion heavy.

In the symbol &, the lower-case, the punctuation-marks, and the numerals the character of the design is preserved.

Having now described my invention, I claim as new—

The design for a font of printing-type, substantially as shown and described.

DAVID WOLFE BRUCE.
